TOY SAVINGS BANK OR SIMILAR ARTICLE

John Berzac, 20536 Cedar, St. Clair Shores, Mich.

Filed Sept. 3, 1959, Ser. No. 57,425

Term of patent 14 years

(Cl. D34—5)

Fig. 1 is a right side elevational view of a toy savings bank showing my new design, taken in the direction of the arrow marked 1 in Fig. 2;

Fig. 2 is a top view thereof, taken in the direction of the arrow marked 2 in Fig. 1; and

Fig. 3 is a front view thereof, taken in the direction of the arrow marked 3 in Fig. 1.

I claim:

The ornamental design for a toy savings bank or similar article, substantially as shown.
